(57) **CLAIM**

The ornamental design for a digital camera display screen with graphical user interface, as shown and described.

DESCRIPTION

FIG. 1 is a rear view of a digital camera display screen with graphical user interface showing my new design;

FIG. 2 is a front view thereof;

FIG. 3 is a right side view thereof;

FIG. 4 is a left side view thereof;

FIG. 5 is a top plan view thereof; and,

FIG. 6 is a bottom view thereof.

The broken line showing is included for the purpose of illustrating portions of the article and forms no part of the claimed design. Additionally the dashed-dotted lines denote the boundary of the claim and form no part of the claimed design.
